UNITED STATES PATENT OFFICE

CHESTER H. BRASELTON, OF NEW YORK, AND FRED B. MACLAREN, OF MALBA, LONG ISLAND, NEW YORK; SAID MACLAREN ASSIGNOR TO SAID BRASELTON

VIBRATION-OPERATED PUMP

Application filed January 30, 1922, Serial No. 532,719. Renewed August 16, 1928.

This invention relates to improvements in the type of machine shown and described in our application for United States patent executed on the 21st day of January, 1922, and filed in the United States Patent Office on January 23, 1922, Serial #531,137, entitled "Method and apparatus for pumping fluids, and our application entitled "Vibration operating pumping mechanism", Serial No. 533,493, filed February 1, 1922, and has to do with modifications in design of the mechanism shown in said applications.

Our embodiment shown in this application is designed and described for use in pumping fluids and in the particular embodiment illustrated to pump liquid fuel for use in self-propelled vehicles from a lower level tank to a higher level auxiliary tank from which the fuel may flow by gravity to a carburetor for an internal combustion engine.

The embodiment shown utilizes the vibration of the vehicle or parts thereof, either when running or subjected to vibration in any such manner as by the operation of the engine, for vibrating an auxiliary tank containing pump mechanism, the piston of which operates as an inertia element so that when the tank containing the pump is vibrated the cylinder of the pump being fixed with respect to the tank will tend to oscillate in the direction of the axis of the piston and relative thereto to thereby cause a decrease and increase in that part of the cylinder cooperating with the piston to cause a pumping effect through suitable valve mechanism to pump liquid from a lower level through the pump and into the auxiliary tank adjacent the latter.

The invention relates to various details of design, operation and construction, economies of manufacture, etc., all hereinafter described and more fully outlined in the appended claims.

In the drawings Figure I illustrates in a conventional way an automobile with our invention applied thereto.

Figure II illustrates a vertical sectional view of the pump tank shown in Figure I.

Referring to Figure I of the drawings, there is shown an application of our inven-

tion applied to an automobile 1 shown in a conventional manner. The engine 2 of the automobile is supplied through manifold 3 with liquid fuel from a carburetor 4. A large tank 5 is located at the rear of the automobile 55 for containing a supply of liquid fuel. This tank is connected through pipe 6 with our pump tank 7, the pipe 6 opening into the upper end of the pump tank. The pump tank at its lower end is connected through pipe 8 60 with the carburetor so that liquid fuel in the tank 7 may flow by gravity to the carburetor as needed.

Our device utilizes the vibration of the tank 7 caused by either the running of the 65 automobile or the vibration of the engine to operate the pumping mechanism. The construction of the pumping mechanism is clearly shown in Figure II which is a vertical longitudinal section of the same. 7 represents a 70 pressed metal tank or receptacle the bottom of which is shown integral with the side. Screwing into an opening 9 in the bottom 10 of the pump tank is a connection 11 adapted to be attached to the upper end of the feed pipe 8 to the carburetor so that liquid 75 fuel may flow from the inside of the tank 7 to the carburetor by gravity. The upper end of the joint 11 is adapted to project slightly above the bottom of the inside of the tank 80 to allow a space in the bottom of the tank in which sediment or water may collect without being drained off to the carburetor. A screw plug 12 is removably attached in the bottom 85 of the tank for draining off the sediment from the bottom of the tank or if desired obtaining liquid fuel for use other than through the carburetor.

A guide 13 is pressed in the inside of the tank and located slightly above the bottom of the same with such a tight fit as to remain permanently in place. This is also preferably made of pressed metal and is of spider formation inside the peripheral ring 13 so as to allow free access of liquid in the tank from 90 above this guide to below it through the openings 14 in the spider. The central part of the spider projects upwardly as at 15 and has an axial hole 16 in which fits the lower end 17 of a piston element 18, the part 15 form- 95 100

ing a guide for the lower end of the piston element. The upper end of the piston element is enlarged at 19 with a boss 20 around which is adapted to fit the upper end of coil spring 21. This spring surrounds the piston element 18 and has its lower end resting upon the top of the spider 13 and being held in place by surrounding the flange 15 of the central portion of the spider. This spring is thus compressed when in place due to the weight of the piston element 18 and enlarged portion 19 and holds the piston element normally at a point of balance from which it may normally be moved relative to the casing 7 from the vibration of the latter. The vibration for operating the pump may be either that caused by the movement of the car over the road, or that of the vibration of the engine when the car is not moving over the road or both of these vibrations together, or the tank 7 may be vibrated manually or by merely shaking the car. We may also provide means for shaking the tank 7 and thus vibrating the same and operating the pump mechanism by mechanical means operated from the engine or elsewhere.

The enlarged part 19 of the piston element has a recess 22 annular in form and opening into the upper surface of this enlarged portion from the top. Inside this annular recess the operating part 23 of the piston is located and which has a bearing on the inside of cylinder 24 projecting down from the top 25 of the casing 7 and into the recess 22. The fit between the piston head 23 and cylinder 24 is a loose fit and the space between the upper end of the piston and the opposing part of the cylinder 24 constitutes the pump chamber. This chamber 26 cooperates with valves 27 in the piston element and 28 in the cylinder element to pump liquid into the tank 7 when relative movement takes place between the piston element and cylinder.

The cylinder 24 has an abutment 29 on its exterior so that when the cylinder is inserted through from the bottom, the cap 25 having a central opening 30, the abutment 29 will rest against the downwardly turned flange 31 on the top 25 in which position it may be soldered or otherwise securely fastened with the top in a liquid tight manner. The upper end of the piston is provided with a nut 32 screwing in a chamber in the upper end of the same and this nut has an axial opening 33 against the lower edges of which the ball valve 27 normally spring pressed upward by the spring 34 between it and the bottom of the recess is positioned. The recess 35 in which the ball valve 27 is located is connected by openings 36 with the exterior of the piston element below the enlarged part 19 and by means of these openings the recess 35 is always in connection for liquid communication with the main chamber of the tank around the bottom part 65 of the piston.

The head 37 for the cylinder has a recess 38 connected with the space 26 and in a counter-bored portion of this recess is screwed a nut 39 having openings 40 for allowing liquid in the valve chamber 38 to flow through to the pump chamber 26. A spring 41 yieldingly holds the ball 28 upwardly in contact with valve seat 42 surrounding the opening 43 in the cylinder head and leading to opening 44, joining transversely with the same. This opening 44 through suitable joint connection is connected with pipe 6 leading from the rear tank and provides an opening and communication from the ball valve 38 and its chamber through the rear tank. In order to provide an adjustable restriction for the flow of liquid from the rear tank into the pump chamber I provide an adjustable screw 45 working in an opening in the head of the cylinder and having a conical lower end cooperating with the valve seat 46 on the upper edge of recess 42. By the use of a lock nut 47 the passage through tube 44 to the ball valve may be held to whatever extent desired.

An opening 48 of very small size is provided in the cap 25 so as to provide atmospheric pressure at all times upon the liquid in the inside of the tank. It is desired that this opening be sufficiently small that any danger from splashing of liquid out of the tank may be eliminated. The cap 25 has turned down flanges 49 at its periphery for fitting snugly over the top of tank casing 7. In order that too tight a fit is not provided for ready removal I provide screws 50 screwing through this flange and into the wall 7 of the tank so as to permanently but removably fasten the lid in place on the tank. A gasket may be provided between the cap and top of the tank wall if desired to make the proper fit.

To facilitate operation of the pump manually if desired we may provide an operating rod 51 the lower end of which is fastened to the upper surface of enlargement 19 of the piston element and the rod projecting through opening 52 in the cap 25 to the exterior of the tank. If it is desired to operate the pump when the casing is not subjected to vibration it then may be done by pushing and pulling the rod 51 upwardly and downwardly to accordingly move the piston. Then too, as shown in Figure I, a handle 53 is pivoted in the dash, its end 54 being adapted to lie over the top 55 of the rod 51. By operating this handle 53 on the dash upwardly its end 54 will be pushed downwardly pushing rod 51 thereunder and with it the piston down in the casing 7. When the handle 53 is released the spring 21 will return the piston and the rod 51 to upward position. By operating the piston in this way manually a few times the tank 7 will be supplied with liquid fuel from the rear tank.

The operation of this device is as follows:

Assuming that as shown in the drawings the device is intended to be used and operated by the vibration of the car when moving over the road or when the engine is running, any movement upwardly of the tank 7 will cause relative movement between the cylinder 24 rigidly carried by the top of the tank 7 and the piston, due to the inertia of the piston which is purposely made sufficiently heavy for this purpose. It is for the purpose of this inertia that the enlargement 19 is formed in the form shown, although the weight may be added at any other place in the piston it being immaterial where the weight is so far as the inertia is concerned. This relative upward movement of the tank and downward movement of the piston operates to draw liquid fuel from rear tank 5 through pipe 6 through opening 44 around conical screw 46 through opening 43 past valve 28 and through openings 40 into the pump chamber 26. As the tank 7 returns downwardly carrying with it cylinder 24 valve 28 closes and valve 27 opens and as the space 26 is reduced in capacity some of the liquid fuel therein flows out through opening 33 past valve 27 and through openings 36 into the liquid containing portion 56 of the tank. Continued or intermittent operation of this sort operates to pump liquid from the rear tank into the chamber 56.

When the chamber 56 is filled with liquid sufficiently to surround or engage the bottom surface of enlargement 19 of the piston 35 this surface, due to the snugness of fit of the enlargement 19 with the inner wall of the tank 7, by its engagement with the liquid in the tank, acts to dampen the vibration of the piston relative to the tank and to cause the two to move in unison. This condition will result until the level of the liquid in the tank is lowered by its being fed out to the carburetor through joint 11 and pipe 8 or to some other receiving mechanism. When the level of the liquid is sufficiently lowered the piston is again free to vibrate with respect to the tank 7 and further pumping will take place upon the vibration of the tank until the liquid is again of sufficient height to engage the bottom surface of the enlargement 19 so that the same will cause a dampening of the oscillation of the piston relative to the tank. In theory this is what happens but in practice as the device is being operated due to the vibration the pumping mechanism will provide a substantially constant level at all times in the liquid chamber of the tank when the tank is designed for the average vibration being used and in such proportions to at all times supply the proper amount of liquid fuel to the carburetor.

Attention is directed to the utility of the inertia chamber 22 in the inertia mass 19 in which the cylinder wall 24 has movement.

The purpose of this chamber is to provide a priming fluid at the initiation of the pumping operation. There is provided sufficient space between the outside of the cylinder and the outer wall of the chamber 22 to permit the inflow of fuel fluid when the level of the same arises in the tank. This fuel accumulates in the chamber 22 and is retained there irrespective of the quantity of fuel which remains in the tank 7, even though the tank 7 should be totally deprived of fuel for any reason. If the pump were perfectly dry there would be difficulty in causing a pumping action because of air leakage between the piston and cylinder wall, and in order to overcome this difficulty the cylinder wall 24, by dipping into the liquid in the chamber 22, carries up a sufficient amount of the same to form a seal and accomplishing what is commonly known as priming. This is one of the noteworthy features of the invention.

Various changes in the design and construction will of course appear to those skilled in the art and without departing from the spirit of our invention. We therefore do not desire that this invention be limited to the particular form of construction shown.

Having described our invention what we claim is:

1. The combination of a receiving tank adapted to be subjected to vibration; a cap for the tank rigidly fastened thereto; a pump cylinder carried by the top of the tank and connected with a supply receptacle, a check valve in the connection between the pump cylinder and the supply tank adapted to allow fluid to pass from the latter to the former but not in the reverse direction; a piston in the pump tank having a portion fitting in the pump cylinder; a fluid receiving chamber in the pump tank; openings connecting said chamber with the pump chamber controlled by a check valve adapted to allow fluid to pass from the pump chamber to the fluid receiving chamber of the tank but to prevent flow thereof in the opposite direction; and means for yieldingly maintaining the piston at a point of balance with respect to the pump cylinder but allowing the piston to move relative to the cylinder as the pump tank is subjected to vibration.

2. In a pumping mechanism the combination of a tank having a top cap; a cylinder attached to said cap; a piston loosely fitted therein; a liquid receiving space around the piston; valve controlled connections between said space and the pump cylinder; valve controlled connections between the pump cylinder and the supply tank; means for causing relative movement between the piston and cylinder by the vibration of the cylinder to pump liquid from the supply tank into the liquid receiving space around the piston and

means adapted to form a liquid seal between the piston and cylinder.

3. The combination of a supply tank; a receiving tank; a piston loosely carried by the receiving tank; a cap for the receiving tank rigidly carried thereby; a pump cylinder carried by the cap and cooperating with the piston to form a pump chamber; means whereby vibration of the receiving tank causes relative movement between it and the piston to pump fluid from the supply tank to the receiving tank; and means including an annular recess surrounding the end of the cylinder and adapted to hold liquid whereby a liquid seal for the piston is provided.

4. The combination of a supply tank; a receiving tank; a piston loosely carried by the receiving tank; a cap for the receiving tank rigidly carried thereby; a pump cylinder carried by the cap and cooperating with the piston to form a pump chamber; a guide for the lower end of the piston in the receiving tank; means whereby vibration of the receiving tank causes relative movement between it and the piston to pump fluid from the supply tank to the receiving tank; and an annular channel formed in said piston and enclosing the end of the cylinder adapted to receive a liquid whereby a liquid seal is provided.

5. The combination of a supply tank; a receiving tank; a piston loosely carried by the receiving tank; a cap for the receiving tank rigidly carried thereby; a pump cylinder carried by the cap and cooperating with the piston to form a pump chamber; a liquid seal between said piston and cylinder comprising an annular channel formed in the piston adjacent the cylinder; means for yieldingly supporting the piston with respect to the receiving tank at a point of balance but adapted to allow relative movement with respect thereto; and means whereby vibration of the receiving tank causes relative movement between it and the piston to pump fluid from the supply tank to the receiving tank.

6. The combination of a supply tank; a receiving tank; a piston loosely carried by the receiving tank; a cap for the receiving tank rigidly carried thereby; a pump cylinder carried by the cap and cooperating with the piston to form a pump chamber; an outlet for the receiving chamber of the receiving tank; and means whereby vibration of the receiving tank causes relative movement between it and the piston to pump fluid from the supply tank to the receiving tank but adapted to reduce said pumping effect when the liquid in the receiving tank stands at a certain level.

7. The combination of a supply tank; a receiving tank; a piston loosely carried by the receiving tank; a top cap for the receiving tank rigidly carried thereby; a pump cylinder carried by the cap and cooperating with the piston to form a pump chamber; means

whereby vibration of the receiving tank causes relative movement between it and the piston to pump fluid from the supply tank to the receiving tank; and additional means for manually reciprocating said piston.

8. In a pump mechanism, the combination of a casing; means including a cylinder and piston within said casing for pumping fluid thereinto, said piston being mounted in the cylinder and said cylinder depending from the top of the casing.

9. In a pump mechanism, the combination of a casing; means including a cylinder and piston within said casing for pumping fluid thereinto, said piston being mounted in the cylinder and said cylinder depending from the top of the casing; and means depending upon the movement of the casing for reciprocating said piston.

10. In a pump mechanism, the combination of a casing; means including a cylinder and piston within said casing for pumping fluid thereinto, said piston being mounted in the cylinder and said cylinder depending from the top of the casing; and a plurality of means, one of which is manual and another of which is automatic depending upon the movement of the casing for causing a pumping action.

11. In a device of the class described, the combination of a casing having base and cap portions; a pump cylinder depending from said cap portion; a piston mounted on said base portion; and a second casing within said piston and adjacent said cylinder.

12. In a device of the class described, the combination of a primary casing; a pump cylinder within and depending from the top of said casing; a piston movable within said cylinder; a weighted mass adapted, through its reciprocation, to move said piston; and a secondary chamber within said mass forming an annular well around the lower end of the cylinder.

13. In a device of the class described, the combination of a casing; a pump cylinder depending from the top of said casing; a piston movable within said cylinder and supported from the base of the casing; an enlarged mass integral with the upper portion of the piston, said mass having an annular cavity formed in the top thereof in which the wall of the cylinder is adapted to have movement, said cavity retaining liquid therein to form a sealing medium for said pump.

In testimony whereof, we affix our signatures.

CHESTER H. BRASELTON.
